UNITED STATES PATENT OFFICE.

PIERRE P. GILLES, OF SPRINGFIELD, MASSACHUSETTS.

CARBURETER.

1,269,177.

Specification of Letters Patent. Patented June 11, 1918.

Application filed May 21, 1917. Serial No. 170,093.

To all whom it may concern:

Be it known that I, PIERRE P. GILLES, born in Switzerland of German parentage, now believing myself to be a citizen of the 5 Swiss Confederation, and having formally declared my intention of becoming a citizen of the United States of America in conformance with the United States immigration laws, and now residing at Springfield, 10 in the county of Hampden and State of Massachusetts, United States of America, have invented certain new and useful Improvements in Carbureters, of which the following is a specification.

15 This invention relates to carburetors and more particularly to carburetors which may be used with and automatically supplied with fuel from a low level supply tank.

An object of the invention is to provide 20 a carburetor having an air-tight fuel-supply chamber adapted for direct connection to a low-level fuel-supply tank, and one or more nozzles connected at one end to the chamber and at the other end to the suction pipe of 25 the carburetor, the construction being characterized in that the nozzles, in addition to their usual function, perform the additional function of vacuumizing said chamber, and 30 constitute the sole means for performing the last-named function.

Another object of the invention is to provide in a carburetor of the class described two fuel passages from the air-tight chamber to the suction pipe, one of which 35 passages has a regulable but substantially constant opening and functions as a slow-speed nozzle and the other of which has an opening which is variable proportionately with the throttle valve opening. The arrangement is characterized in that both 40 nozzles function as the sole means for creating a vacuum in the air-tight chamber.

Other objects and advantages will appear 45 in the following description and will be particularly pointed out in the appended claims.

The invention is shown for illustrative purposes in the accompanying drawings, in which—

50 Figure 1 is a top plan view of a carburetor embodying the invention;

Fig. 2 is a cross sectional view taken on the line 2—2 of Fig. 1;

Fig. 3 is an enlarged detail sectional plan view taken on the line 3—3 of Fig. 2;

Fig. 4 is a sectional elevation taken on the line 4—4 of Fig. 1;

Fig. 5 is a sectional plan view taken on the line 5—5 of Fig. 2;

Fig. 6 is a fragmentary sectional view 60 taken similarly to Fig. 4 and illustrating a modification of the invention; and

Fig. 7 is a cross sectional view taken similarly to Fig. 2 and illustrating a further modification of the invention. 65

Referring to these drawings in detail and particularly to Figs. 1 to 5, inclusive, the carbureter casing comprises a substantially horizontal suction pipe 10 which is open at both ends and adapted for attachment by the flanges shown to the intake manifold of the engine, and a tank 11 which is preferably integral with pipe 10 and is closed at the top by a suitable cover 12. A fuel inlet pipe 13 (Fig. 1), removably secured to cover 12 (Fig. 4), is connected at one end through openings in the latter to the upper part of tank 11. The other end of pipe 13 is adapted for connection directly with a suitable fuel supply tank, not shown, 70 such as a low level supply tank in an automobile, for example. 75

Referring to Fig. 5, adjacent the air inlet end of pipe 10 an air choke valve 14 is provided which is pivotally mounted in pipe 80 10 with its axis vertically disposed, and may be operated by a suitable lever 15 (Fig. 1). Spaced from the choke valve 14 is a throttle valve 16 secured by the screw shown in Fig. 5 to a sleeve 17, which, as shown in Fig. 2, 85 is vertically and rotatably mounted in pipe 10. Fixed to the upper end of sleeve 17 is a suitable lever 18 for turning the sleeve and thus throttle 16. Threaded into sleeve 17 from the upper end thereof is a needle 90 valve 19 which may be raised and lowered in the sleeve to open and close the upper end of an axial passage 20 leading to the lower end of the sleeve. The throttle 16 and sleeve 17 are formed with registering 95 openings 21, through which fuel, drawn through passage 20 in a manner to be described, may pass into the suction pipe 10. Valve 19 has been purposely shown as broken away to reveal the openings 21. It 100 is to be particularly noted that openings 21 open into pipe 10 at a point between the axis of the throttle 16 and the engine end of the pipe (see Fig. 5). 105

Threaded into the under side of pipe 10 110

and below the base of sleeve 17 is a casing 22 (Fig. 2), the axis of which is parallel with but slightly offset from the axis of the sleeve. Casing 22 is connected near its lower end by a pipe 23 to the described tank 11. A valve 24 is normally held to its seat in casing 22 by a spring 25 which acts between a shoulder in casing 22 and a nut 26 threaded on the stem 27 of the valve. Referring to Fig. 3, the nut 26 is substantially square so that fluid admitted by valve 24 may flow past the valve through spaces 28 and thence into the described passage 20 in sleeve 17. Stem 27 is forced against the base of the latter by spring 25 and may be raised and lowered by a cam 29 formed on the base of the sleeve. When the throttle 16 is closed, valve 24 is closed, and, as the throttle is opened, valve 24 does not immediately open until the throttle has moved a slight amount for a reason to appear. On continued movement of throttle 16, however, valve 24 is opened proportionately therewith.

26 The openings 21 and their connections with tank 11 constitute the main nozzle for the carburetor. Another nozzle, commonly called a slow speed nozzle, is provided which will now be described. Referring to Fig. 5, a horizontal passage 30 intersects pipe 10 at right angles and emerges into the pipe at such a position that it is closed off by damper 16 when the latter is entirely closed. Passage 30 is connected by a vertical passage 31 (Fig. 4) to a horizontal passage 32 which in turn connects with a vertical passage 33 opening downwardly into tank 11 through cover 12. The effective opening of passage 33 into tank 11 is regulable by a needle valve 34 which also closes the upper end of passage 33.

The tank 11 is made air tight except for the fuel passages connecting therewith as described and is connected by pipe 13 directly to the fuel supply tank. The main and slow speed nozzles described may be placed in communication with the air tight tank 11 by manipulating the valves 15, 16, 19, and 34, in a manner later to be described in detail, so that the suction of the engine through pipe 10 is also effective upon the tank to establish a partial vacuum therein. Thus, fuel may be drawn from the main fuel supply tank through pipe 13 and its connections to tank 11 and thence may be delivered into pipe 10 through either or both of the described inlets thereto, in a manner which will be later described in detail.

60 Although it is preferred to have tank 11 air tight, the invention may be used with a tank which is not wholly air tight, as the only essential is to create a sufficient degree of vacuum in the tank to draw fuel from the main supply tank. Thus, in Fig. 6 a

passage 35 may be provided to connect the passage 34 with the atmosphere. The provision of the passage 35 makes it possible to deliver air with the fuel supplied by passages 30, 31, 32, and 33 to the suction pipe as 70 will be described. A needle valve 36 has a flange 37 which partitions the passage 33 and closes off the upper part of the latter from tank 11 and passage 35 except for a small axial opening 38 in the valve which is 75 connected by lateral openings above the flange 37 to the passage 33. The lower end of valve 36 is formed with a conical recess which is adapted to coöperate with the conical upper end of a bushing 39 having a 80 small axial passage 40 therethrough. By turning the valve 36 down into engagement with member 39 the air supply from passage 35 to passage 33 may be entirely closed off, leaving merely a relatively small passage for 85 fuel from the tank 11 to passage 33. By opening valve 36 the degree of vacuum in tank 11 may be diminished slightly and air may be mixed with fuel prior to its entrance to the suction pipe 10.

86 Instead of providing the relatively large tank 11, a small chamber 42 may be provided below the valve 24 as shown in Fig. 7. Chamber 42 is connected from below to the main fuel supply tank by a pipe 43 and a ball check valve 44 is provided in casing 42 to prevent return of fuel through pipe 43. Chamber 42 is connected by pipe 45 to a circuitous passage 46 which is formed in an integral exterior extension of pipe 10 and 100 emerges into the pipe to form a slow speed nozzle. A needle valve 47 is interposed in passage 46 to control the effective opening thereof in an obvious manner. The main nozzle is identical with that already described and throttle and choke valves 16 and 14, respectively, are used as heretofore. The passage 46 also delivers into pipe 10 at such a point that it may be closed off by the throttle valve 16 when the latter is in closed 110 position.

105 The operation of the carburetor will now be described. With the embodiment of the invention shown in Figs. 1 to 6, inclusive, the tank 11 may be originally filled with fuel in the following manner. The choke valve 14 is entirely closed and throttle 16 is opened sufficiently to uncover the opening of passage 30 into suction pipe 10. Needle valve 34 is opened wide as shown in 120 Fig. 4, so that a strong suction from the engine is obtained to create a partial vacuum in tank 11 to draw fuel into the latter from pipe 13. Throttle 16 may also be opened wide at the start of the filling operation to 125 assist in removing the air from tank 11 but should be closed off before the tank is completely filled. Thus, with the valve 24 closed, the tank 11 may be completely filled by the suction through pipe 10 which may 130

be made of relatively high degree by closing the choke valve 14. The tank 11 of the carburetor may be originally filled by this method when first installed, or by any other suitable source of suction. The suction applied to passage 30 is continued until fuel begins to flow therein and the flow of fuel into passage 30 furnishes a convenient indication that the tank is completely filled and ready for operation.

In normal operation, the needle valve 34 is adjusted to permit only a relatively small amount of fuel to pass thereby. As compared to the valve 34, the needle valve 19 is adjusted to permit a relatively large flow of fuel thereby. Both the main and slow speed nozzles are, however, regulable as desired and may be adjusted by experimentation to secure the desired results. On starting the engine, the choke valve 14 is preferably closed while the throttle valve 16 is widely opened. The opening of the latter opens valve 24 and fuel is drawn through the passage 30 and openings 21 by the suction of the engine applied to pipe 10. Since the choke valve 14 is closed, a relatively strong suction is available to draw a rich mixture into the engine. As a matter of fact, the fuel level in tank 11 is somewhat higher than the openings 21, so that an immediate flow through the latter would be obtained by gravity action as soon as valve 24 is opened. This is desirable at starting. The flow by gravity cannot take place to any considerable extent, however, as the described difference in level is not great and, if desired, may be eliminated entirely as in Fig. 7.

After the starting operation, the choke valve 14 is opened and thereafter the throttle valve 16 only is manipulated which causes a proportionate opening of the fuel controlling valve 24 for the main nozzle. Thus, an increase in air is accompanied by a corresponding increase in fuel. The suction of the engine is always effective through passage 30 immediately as it is uncovered by a slight opening of throttle 16 to draw fuel from tank 11. If the fuel level has, however, dropped due to the gravity flow described, the suction through passage 30 will first act to replenish the tank, but thereafter there will be a flow of fuel therethrough proportionate to the amount of suction in pipe 10. This flow may be made as small as desired by regulation of valve 34. The flow through the main nozzle may be regulated by the needle valve 19 to vary the proportion of fuel to air. In normal operation, however, the valve 24 controls the flow by diminishing the effective opening through which the suction is available to act on tank 11 at times of relatively large suction in pipe 10 as when throttle 16 is nearly closed and by increasing the opening as the

throttle is opened to permit a larger effective opening through which the suction may act on the tank at times of relatively low suction. The variations described are based, of course, upon the assumption that the engine speeds in both instances are equal. At times when the throttle is wide open and the degree of vacuum in pipe 10 is lower than usual, due to decreased engine speed, as when traveling on an upgrade; for example, if the engine is used in an automobile, a reserve supply is in effect obtained by the flow which may take place from tank 11 by gravity as described. On slow speeds, the throttle 16 may be closed sufficiently to close valve 24 and yet leave the passage 30 uncovered. When the parts are thus positioned, a relatively strong suction is obtained, which although effective only through a relatively small opening is nevertheless sufficient to supply fuel in the desired quantity.

With the arrangement shown in Fig. 7, the chamber 42 being relatively small may be rapidly filled by opening the throttle 16 while choke valve 14 is entirely closed. Both nozzles may be utilized in the preliminary filling of the chamber. The operation of the carburetor shown in Fig. 7 is otherwise similar to that above described. With both forms, the fuel from the main nozzle may be gradually diminished on relatively slow engine speeds and may be entirely closed off at very slow speeds, leaving the supply of fuel entirely to the slow speed nozzle, as it will be remembered that the passage 30 is not closed off until throttle 16 is entirely closed while valve 24 is arranged to close before the throttle.

The invention is characterized in that the fuel nozzles themselves constitute the means for drawing fuel from the main fuel supply tank. A gravity supply with the usual float controlled valve is unnecessary as are also the vacuum fuel feeding devices which draw fuel by suction from a low level fuel supply tank and thereafter feed the fuel by gravity to a carburetor. Such fuel feeding devices involve float controlled valves, as do also the carburetors which they supply, while in the present invention such valves are unnecessary and a supply of fuel from a low fuel supply tank may be effectively obtained by comparatively simple means. The intermediate devices heretofore arranged between the nozzles and the main fuel supply tank may thus be eliminated. As against the former carburetors and fuel supply devices therefor, the present invention employs substantially but a suction pipe and nozzles and connections from the latter to the main fuel tank.

The invention has been described in a preferred form with detailed variations for the purposes of illustration, but the scope

of the invention is defined by the appended claims rather than by the foregoing description.

What I claim is—

- 5 1. A carbureter, comprising, an air intake passage adapted for connection to suction means, an air-tight chamber having a passage which is adapted for connection with a low-level fuel-supply tank and constitutes the sole connection between the tank and chamber, and an air-tight fuel passage between the latter and said intake passage arranged so that the suction applied to the fuel passage is operable to create a vacuum 10 in said chamber and completely fill the latter from said tank.
- 15 2. A carbureter, comprising, an air intake passage adapted for connection to suction means, a throttle valve in said passage, an air-tight chamber having a passage which is adapted for connection with a low-level fuel-supply tank and constitutes the sole connection between the tank and chamber, an air-tight fuel passage between the latter and said intake passage arranged so that the suction applied to the fuel passage is operable to create a vacuum in said chamber and completely fill the latter from said tank, and a valve in the fuel passage operably connected to the throttle valve to be opened and closed by the opening and closing of the throttle valve.
- 20 3. A carbureter, comprising in combination, an air intake passage adapted for connection to suction means, an air-tight chamber adapted for direct connection to a low-level fuel-supply tank, and fuel-conducting means connecting said passage and chamber and affording air-tight communication therebetween, all constructed and arranged so that the suction applied to the fuel-conducting means is operable to create a vacuum in said chamber, whereby the latter may be filled from the low-level tank, 25 said fuel-conducting means constituting the sole means of creating a vacuum in said chamber.
- 30 4. A carbureter, comprising in combina-

tion, an air intake passage adapted for connection to suction means, a throttle valve in said passage, an air-tight chamber adapted for direct connection with a low-level fuel-supply tank, a fuel passage connecting said chamber and intake passage, means to vary the effective opening of said fuel passage proportionately with the variations of the intake passage by said throttle valve, and a second fuel passage connecting said chamber and intake passage, and affording a communication therebetween which is of constant effective area, said first and second fuel passages constituting high-speed and slow-speed nozzles, respectively, all constructed and arranged so that the high and slow speed nozzles constitute the sole means of creating a vacuum in said chamber to fill the latter from the low-level tank.

5. A carbureter, comprising in combination, an air intake passage adapted for connection to suction means, a throttle valve in said passage, a chamber in which a partial vacuum may be established and adapted for direct connection with a low-level fuel supply tank, a main fuel passage connecting said chamber and intake passage, a secondary fuel passage connecting the latter and said chamber, said main and secondary passages constituting high speed and slow speed nozzles, respectively, and constituting the sole means of creating a vacuum in said chamber to fill the latter from the low level tank, means to vary the effective opening of the main fuel passage proportionately with the variations of the intake passage by said throttle valve and operable to assist in controlling the fuel level in said chamber, and controlling means operable for any given degree of opening of the throttle valve to regulate the suction effective through the secondary fuel passage on said chamber and arranged to control for any given degree of throttle opening the distribution of fuel between the high speed and slow speed nozzles.

PIERRE P. GILLES.
